BARREL RECOIL GUN.

1,089,078.

Specification of Letters Patent. Patented Mar. 3, 1914.

Application filed August 1, 1910. Serial No. 574,810.

To all whom it may concern:

Be it known that I, HEINRICH RABBA, a subject of the Emperor of Germany; and a resident of 27 Dorotheenstrasse; Essen-on-the-Ruhr, Germany, have invented certain new and useful Improvements in Barrel Recoil Guns, of which the following is a specification.

This invention relates to barrel recoil guns in which the gun barrel consists of a separable tube and jacket.

The invention improves on guns of this kind in that a separate locking device between the tube and jacket will not be needed. The problem is solved in this invention with having the gun barrel connected in such a manner with the slide intended for guiding the gun barrel on the guide-carrier or cradle, that the means connecting the gun barrel with the slide also serves to prohibit the severing of the connection between tube and jacket.

In the drawing is illustrated one embodiment of the invention, and it shows in Figure 1 partly a side view and partly a longitudinal section of the parts of a barrel recoil gun that are under consideration; Fig. 2 is an end view partly in section and partly in elevation; and Figs. 3 to 5 are sections through lines 3—3, 4—4 and 5—5 of Fig. 1 seen from the right.

The gun barrel consists of a tube A, and a jacket B which incloses only the rear end of the tube and at the same time constitutes the breech end of the gun barrel. A bayonet-lock is used to connect the tube with the jacket, and it consists of four rows of annular ribs a¹ on the tube, engaging with corresponding ribs b¹ and grooves b² in the jacket (Figs. 1 and 5).

The gun barrel rests on a slide C, that in well known manner carries the gun barrel on the guide-carrier or cradle D, and connects it both with the recoil brake and the recuperator. The connection between the gun barrel and the slide C is arranged as follows. The breech end of the jacket B carries a projection b³ (Figs. 1 and 2) at the lower end of its rear face and which is disposed at right angles to the axis of the bore of the gun barrel. Said projection has a semicylindrical surface as indicated by b⁴ (Fig. 1). The slide C is provided with an open bearing c¹, within which fits the projection b³. The part of the bearing c¹ that

reaches over the projection b³ has such a shape that the jacket B may be partially tilted upward around the axis of the semi-cylindrical surface b⁴ of the projection b³. The jacket B lies with its forward end 60 against a projection c² (Fig. 1) on the slide C. The tube A rests with a projection a² (Figs. 1, 3 and 4) near the muzzle on a bearing-block c³, c⁴ of the slide C. This bearing-block is L-shaped as seen in plan 65 view. The part c³ of the bearing block c³, c⁴ being at right angles to the longitudinal middle line of the slide carries a lip or ledge c⁵ (Figs. 1 and 3) turned toward the muzzle of the gun barrel and engaging with another lip or ledge a³ on the projection a² of the tube A. The ledges a³, c⁵ as well as the surfaces of the projection a² and of the bearing-block c³, c⁴, which serve as bearing surfaces, are arranged all concentric to the 70 axis of the bore of the gun barrel. This arrangement permits the turning of the tube A in the jacket B resting on the slide C. A rotatable bolt E (Figs. 1 and 4) which cannot be withdrawn, is carried in 75 the cheeks c⁴ of the bearing-block c³, c⁴, at right angles to the axis of the bore of the gun barrel. This bolt E has an operating handle e¹ (Fig. 1) and can engage with the projection a² of the tube A. The bolt is 80 provided with several ribs e¹ extending at right angles to the axis of the bolt and designed to enter corresponding grooves in the projection a² on the tube. The bolt E has further a recess e² (Fig. 4) which is so formed that the tube may be turned around and drawn out against the slide C, when the recess e² is turned toward the face a⁴ of the projection a², i. e. when the bolt is turned 85 180° from the position shown in the drawing.

When the gun barrel is connected to the slide C, the parts take the position shown in the drawing, and thus will the jacket B be prevented from turning on the slide, through 90 the entering of its projection b³ into the bearing c¹; and through the bearing c¹ and the projection c² from shifting on the slide. The tube A is, through the above mentioned bayonet-lock, connected to the jacket and 95 rests on the block c³, c⁴ of the slide. The bolt E and its ribs e¹ enter into the projection a² of the tube, so that the tube is secured from turning. The lips a³, c⁵ engage with each other, thus preventing the tube from 100 105 110

swinging when the gun is fired. To dismount the gun, the bolt E, by means of its handle e³ is turned 180°. Then the tube is turned in the jacket so as to allow the ribs 5 a¹ to enter the grooves b² of the jacket, and the tube is free to be drawn out of the jacket. The jacket may then be removed from the 10 slide, after it has been partly raised (at the muzzle end) around the axis of the semi-cylindrical surface b⁴ of the projection b⁵.

How to mount the gun barrel on the slide needs no explanation after the above description. It should be mentioned, however, that the means of connecting the tube with 15 the slide permit of the connecting of the tube with the jacket, after the latter has already been placed on the slide.

The described arrangement renders unnecessary a separate locking device in the 20 connection of the tube with the jacket. It provides, besides, a sure connection between the gun barrel and the slide and furthermore it permits of an easy mounting and dismounting of the gun, as the jacket and tube 25 may be laid on the slide separately and also taken off separately.

I claim:—

1. In a recoiling gun with a separable gun barrel, the combination of a jacket, a tube 30 detachably connected to the jacket by a bayonet-lock and forming therewith the barrel, a slide for guiding the gun barrel on the guide-carrier, said jacket having connection with the slide and said tube and slide having 35 inter-engaging faces arranged concentric with the axis of the gun barrel, a bolt disposed transversely of and engaging with the tube to interlock said engaging faces, a recess in said bolt adapted to permit the 40 rotation of the tube when said bolt is turned a half revolution.

2. In a recoiling gun with a separable gun barrel, the combination of a jacket, a tube 45 detachably connected therewith by a bayonet-lock and forming therewith the barrel, and a slide for guiding the gun barrel on the guide-carrier said jacket having connection with the slide, said tube and slide having 50 engaging faces arranged concentric with the axis of the gun barrel, means engaging with the tube to prevent separation between the slide and the gun barrel, said means making engagement between the tube and the slide and preventing separation between 55 the tube and jacket.

3. In a recoiling gun with a separable gun barrel, the combination of a jacket, a tube 60 detachably connected therewith by a bayonet-lock and forming therewith the barrel, a slide for guiding the gun barrel on the guide-carrier, said jacket having connection with the slide and said tube and slide having 65 inter-engaging faces arranged concentric

with the axis of the gun barrel, and a bolt disposed transversely of and engaging 70 with the gun barrel and interlocking said engaging faces, and coöperating with the engagement between the jacket and the slide to prevent unlocking of the bayonet-lock of the tube and jacket.

4. In a recoiling gun with a separable gun barrel, the combination of a jacket, a tube 75 detachably connected therewith by a bayonet-lock and forming therewith the barrel, a slide for guiding the gun barrel on the guide-carrier, said jacket having connection with the slide, and said tube and slide having 80 interengaging members arranged concentric with the axis of the gun barrel, a plurality of grooves formed within a face of the tube adjacent said members and a locking bolt having ribs mounted on the slide and adapted to engage with said grooves and hold the engaging members interlocked; said connections between the tube 85 and the jacket with the slide adapted to prevent unlocking of the bayonet-lock of the tube and the jacket.

5. In a recoiling gun with a separable gun barrel, the combination of a jacket, a tube 90 detachably connected to the jacket by a bayonet-lock and forming therewith the barrel, a slide for guiding the gun barrel on the guide-carrier, said jacket having connection with the slide and said tube and slide having 95 interengaging faces arranged concentric with the axis of the gun barrel, a bolt disposed transversely of and engaging with the gun barrel to interlock said engaging faces, and means connecting the jacket and the 100 tube to the slide to prevent dismounting of the jacket from the slide.

6. In a recoiling gun with a separable gun barrel, the combination of a jacket, a tube 105 detachably connected to the jacket by a bayonet-lock and forming therewith the barrel, a slide for guiding the gun barrel on the guide-carrier or cradle, means for connecting the gun barrel to the slide, said means being adapted to prevent simultaneously the 110 unlocking of the bayonet lock and thereby the separation of the tube from the jacket, said connecting means comprising a straight ledge and groove at the breech end, and an arcuate ledge and groove near the muzzle 115 end of the barrel, and a transverse collar bolt adjacent said arcuate ledge.

The foregoing specification signed at Barmen, Germany, this 12th day of July, 1910.

HEINRICH RABBA. [L. S.]
